UNITED STATES PATENT OFFICE.

CLINTON C. BUCHANAN, OF BARTOW, FLORIDA, ASSIGNOR OF ONE-THIRD TO JOHN J. BOYNTON AND ONE-THIRD TO SOLON G. WILSON, BOTH OF BARTOW, FLORIDA.

PLOTTER.

1,142,077.

Specification of Letters Patent. Patented June 8, 1915.

Application filed November 18, 1913. Serial No. 801,712.

To all whom it may concern:

Be it known that I, CLINTON C. BUCHANAN, a citizen of the United States, residing at Bartow, in the county of Polk and State of Florida, have invented certain new and useful Improvements in Plotters; and I do declare the following to be a full, clear, and exact description of the invention, such as will enable others skilled in the art to 10 which it appertains to make and use the same.

This invention relates to drafting, and more especially to plotters; and the object of the same is to produce an instrument 15 adapted more particularly for use in drawing the outline of plots of ground such as farms, lots, etc., on large sheets of paper, which latter may or may not be inscribed with lines indicating townships, sections, 20 etc.

The invention comprises a drawing board, a ruler movable thereover in directions at right angles to each other, a protractor movably mounted within the ruler, and wings 25 or straight-edges carried by said protractor and against which lines can be drawn at any desired angle.

Details of the invention will be found in the following specification and are shown in 30 the accompanying drawings wherein—

Figure 1 is a plan view of this invention. Figs. 2, 3, and 4 are sectional views on the lines 2—2, 3—3, and 4—4 respectively of Fig. 1. Fig. 5 is a detail of the protractor 35 and its wings taken on about the line 5—5 of Fig. 2; and Fig. 6 is a plan view of a slightly modified form of protractor.

In the drawings the numeral 1 designates a base board, 2 and 3 are side strips, and 4 is a lower edge strip secured to the face of the board and chamfered or recessed along their inner lower corners as at 5 so that they overhang the face of the board as seen in the 45 sectional view, the upper inner corners of the side strips being cut away as at 6.

7 is an upper or guide strip connecting the side strips 2 and 3 near their upper ends but below their cut-away corners 6, and this upper strip is sustained at a slight distance 50 above the face of the board to correspond with the grooves or recesses 5 as shown. This construction permits a piece of paper P to be slipped over the face of the board between the corners 6, under the strip 7, and 55 along the grooves within the other three

strips so that it will closely overlie the board and cannot become displaced. Upon the faces of the four strips which form a frame around the "sight" of the board, are secured strips 8 which are preferably of celluloid, marked with graduations 9 along their inner edges.

The numeral 10 designates a ruler preferably having graduations 11 along both its edges, and each end of this ruler is recessed or chamfered as at 12 along its under side so that it will overhang the side strips 2 and 3 or the upper and lower strips 4 and 7, and the shoulders 13 will fit closely but slidably against the inner edges of either pair of strips so that the ruler is maintained ever in a position with both its edges parallel with the inner edges of one pair of strips and at strict right angles to the inner edges of the other pair. The overhanging ends 75

14 of the ruler slide on the celluloid face plates or strips 8 whose graduations may be read as a guide for setting the ruler, and the graduations 11 along either edge of the ruler itself may be read as a guide for finding any transverse point on the paper P between the strips 8. Where the paper is inscribed with faint lines as often employed to indicate quarter sections and their subdivisions, the graduations on the frame strips and on the edges of the ruler should correspond, although obviously this is not absolutely necessary, as the graduations may be in inches and fractions thereof or on the metric system without departing from the 80 spirit of my invention. The ruler is made up of a body portion 16 which may be of metal, dropped at its center to produce the shoulders 13, and yet whose lower face does not contact with the paper when its ends 14

rest on the side strips 8; and a celluloid face 85 17 overlying and spaced from said body portion between the ends of the latter and inscribed with the graduations 11 referred to. Through the body and the face plate of the 90 ruler is formed a longitudinal slot 18.

Movably disposed within the ruler between its body and face plate is a protractor 20 which is by preference formed in the shape of a metal disk whose diameter equals the 95 width of said ruler and is inscribed around its edge with graduations 21 as usual, and an integral wing 22 projects from one side of this protractor, one edge 23 of the wing being tangential to the protractor body and 100 110

the other edge 24 being radial thereto. In Fig. 6 a slight modification of this protractor is shown wherein it has two wings, the opposite wing 22' having similar edges 23' and 24' but being disposed on the other side of the protractor body in such position that its edge 24' will align with the radial edge 24 of the first-mentioned wing 22. The construction is such that the wing (or wings) 10 may be housed entirely within the ruler as seen in dotted lines in Fig. 1, or the protractor may be turned on its center so that the wing projects beyond either edge of the ruler and may be set at the desired angle thereto. Rising rigidly from the center of the protractor is a stem 25 having a threaded body and its upper end preferably made square or annular as at 26 to receive a knob 27 which may be held in place by any suitable means such as a screw 28; and on the shank of this stem is screwed a nut 29 which may be set down tight against the face plate 17 of the ruler to hold the protractor after the latter has been adjusted. Loosely mounted on the threaded portion of the stem 25 is a block 30 which projects upward into the slot in the face plate beneath the nut 29 although not sufficiently far to make contact with the nut when the latter is screwed down onto the celluloid; and this block carries an integral finger or index 31 which projects toward one edge of the ruler and closely underlies the celluloid while it overlies the face of the protractor 20 and its tip 30 coacts with the graduations 21 thereon. With this detailed construction of parts, when the nut is loosened the knob 27 may be grasped to rotate the protractor and its wing or wings so that its graduations pass under the tip of the index and either edge 23 or 24 may be set at any desired angle to the horizontal line indicated by the upper or lower edge of the ruler; or when the ruler is turned one-quarter way over the face of the board 1, its edges will be upright or vertical to the eye, and the protractor may be set to any desired angle to them.

The operation or use of this device is as follows: A sheet of card or paper P is 50 slipped over the face of the board 1 by passing it under the upper strip 7 and sliding it along the grooves 5 in the side strips 2 and 3, and when it comes to rest in the groove in the lower strip 4 it will be accurately centered within the frame above referred to. In fact the paper may be printed with a square outline indicating the "sight" and what remains may well constitute a margin in which there is no drawing. The 55 ruler 10 is then laid over the board with its ends 14 resting on an opposite pair of strips, and when moved along said strips the graduations on the latter can be read to find the exact position of either edge of the ruler.

60 Reading the graduations 11 along this edge

of the ruler, the operator can then find his exact position at any point over the face of the paper, and we will assume that this is the point where he commences to sketch the farm, lot, or other piece of property 70 which is to be drawn onto the paper. So long as the user is drawing straight lines which are strictly horizontal or strictly vertical, he may use the ruler, disposing the same as seen in Fig. 1 when he desires to 75 draw horizontal lines and turning it to an upright position when he desires to draw vertical lines. Or it is obvious that he may use a small triangle such as ordinarily employed by draftsmen and rest the base of the 80 same against one edge of the ruler so that the other edges of the triangle may be employed for drawing on the paper. This is the common practice and needs no illustration. But with the use of the protractor 85 above described, it is quite possible to turn the same so that the user may work against either edge 23 or 24 of its wing, and by setting the graduations 21 of the protractor under the index 31, either of said edges may 90 be disposed at the proper angle to either straight edge of the ruler. Therefore the protractor itself may be employed for drawing vertical lines, while the edges of the ruler may be employed for drawing horizontal lines. Ordinarily the boundary lines 95 of farms and lots follow vertical and horizontal lines on the sheet P, although in some communities where a large tract has been subdivided, the farms, lots, or smaller divisions of the large tract will often follow the general outline of the boundaries of said tract so that if the latter stood oblique to a vertical and horizontal, the boundary lines of all the sub-divisions would doubtless stand 100 on the same angle. In this case, having once set the protractor with either of its edges on this angle, all the boundary lines on the same angle could be quickly found, and those at right angles thereto could be 105 ascertained by placing a triangle against the edge of the protractor wing.

The use of the double-winged protractor shown in Fig. 6 is the same as that of the single-winged protractor illustrated in Fig. 115 1, excepting that with two wings parallel lines can be more quickly found and a longer diametric line can be drawn along the edges 24 and 24'. With the single wing, however, lines can be drawn nearer to the inner edges 120 of the frame. In Fig. 1 of the drawings I have designated the outline of a farm as indicated at F, whereof the side lines stand at about 20° from a vertical line whereas the north and south end lines are strictly 125 horizontal. The last-named lines can obviously be drawn with either edge of the ruler, whereas the side lines would have to be found by means of the protractor. It is quite possible that the graduations along the 130

edges of the ruler, the side strips of the frame, and both edges of the wing or wings of the protractor could be marked with figures to designate distances, and the result 5 would be that in drawing or plotting farms, lots, or other tracts of land, the draftsman would not then need a ruler to measure the length of any line because the edge over which he was drawing that line would be 10 sufficient.

I do not wish to be limited to the materials or proportions of parts, and changes in details may be made without departing from the spirit of my invention.

15 What is claimed as new is:

1. In a plotter, the combination with a drawing board having parallel strips along its sides; of a ruler movably mounted over the board and fitting slidably between said strips, its body being longitudinally slotted, a block slidably mounted in said slot and having an index, a protractor pivotally mounted on said block and having graduations adapted to coact with said index, and a wing 25 projecting from said protractor, one edge of the former being radial and the other tangential to said protractor.

2. In a plotter, the combination with a drawing board having parallel strips along 30 its sides; of a ruler movably mounted over the board and fitting slidably between said strips, its body being longitudinally slotted, a block slidably mounted in said slot and having an index, a protractor pivotally 35 mounted on said block and having graduations adapted to coact with said index, and a pair of wings projecting from opposite sides of said protractor, one edge of each wing being radial and the other tangential to the protractor.

3. In a plotter, the combination with a drawing board having parallel strips along its sides; of a ruler movably mounted over the board and fitting slidably between said strips, the ruler having a body and an overlying transparent face plate, the latter provided with a longitudinal slot, a block overlying the body and projecting partway into said slot, a rigid index carried by said block, 45 between said body and face plate and standing on a line at right angles to the length of said slot, a protractor disposed above said body and beneath said block and index and having a circular row of graduations 50 coacting with the tip of the index, a stem rising rigidly from the axis of said protractor and passing loosely through said block and slot and having a knob at its upper end, and means for holding said stem 55 after the protractor has been set.

4. In a plotter, the combination with a drawing board having raised strips along its edges, of a ruler comprising a body dropped at its center so as to produce outwardly facing shoulders which slide against

the inner edges of said strip and projecting ends which overlie said strips, the latter being graduated and the edges of the ruler also being graduated, a transparent face plate overlying the dropped portion of the ruler and having therein a longitudinal slot, a protractor rotatably intermediate said face plate and dropped portion of the ruler, an index disposed immediately above the protractor for coöperation with the latter, said index having a portion thereof projecting partway into said slot substantially as and for the purpose set forth.

5. In a plotter, the combination with a drawing board, raised strips along three 80 sides of the same cut away at their inner lower corners, a strip along the remaining side of the board and raised above the face of the latter, the upper inner corners of the side strips being cut away above the last-named strip, transparent face plates on all 85 said strips, and graduations on the face plates; of a ruler having a dropped center and projecting ends adapted to overlie a pair of said celluloid face plates, for the 90 purpose set forth.

6. In a plotter, the combination with a drawing board having parallel strips along its sides; of a ruler movably mounted over the board and fitting slidably between said strips, the ruler having a body, and an overlying transparent face plate, a protractor rotatably mounted intermediate the plate and said body, an index disposed above said protractor, means to retain the former in fixed 100 relation to a predetermined point on the latter, a wing projecting from said protractor, one edge of said wing being radial and the other tangential to said protractor, and means for rotating the latter.

7. In a plotter, the combination with a drawing board having parallel strips along its sides; of a ruler movably mounted over the board and fitting slidably between said strips, the ruler having a body, and an overlying transparent face plate, a protractor rotatably mounted intermediate the plate and said body, an index disposed above said protractor, means to retain the former in fixed 110 relation to a predetermined point on the latter, a pair of wings projecting on opposite sides of the protractor, one edge of each wing being radial and the other tangential to the protractor, and means for rotating the latter.

8. In a plotter, the combination with a drawing board having parallel strips along its sides; of a ruler movably mounted over the board and fitting slidably between said strips, the ruler having a body, and an overlying transparent face plate, a protractor rotatably mounted intermediate the plate and said body, said protractor having a diameter corresponding to the width of said plate and said body, a wing projecting from 125

130

said protractor one edge of said wing being radial and the other tangential to said protractor, means to rotate the latter and incidentally to house the wing thereon between said plate and said body, an index disposed immediately above said protractor in fixed relation to a predetermined point thereon and means for maintaining said protractor in adjusted position.

10 9. A ruler for the purpose set forth comprising upper and lower spaced apart members, a protractor rotatably mounted intermediate said members, an index disposed immediately above said protractor, means to

maintain said index in fixed relation to a 15 predetermined point on the protractor, a wing projecting from said protractor, one edge of said wing being radial and the other tangential to said protractor, and means for rotating the latter.

20 In testimony whereof I have hereunto set my hand in presence of two subscribing witnesses.
